UNITED STATES PATENT OFFICE.

FERNANDO CASABLANCAS, OF SABADELL, SPAIN.

DRAWING MECHANISM FOR TEXTILE ROVINGS.

Application filed August 18, 1922, Serial No. 582,722, and in Spain September 10, 1921.

My invention relates to the drawing of textile materials and more particularly to a drawing mechanism adapted to effect on the roving two or more successive drawings in a single machine.

In my co-pending patent application Ser. No. 472,453 there is described a drawing mechanism for textile rovings in which there are combined feeding devices of the types employed for permitting large drawings, which feeding devices are so arranged that in addition to the usual movement for bringing the roving very close up to the line of contact of the drawing rollers, they possess a rotary movement around the axis of the roving for the purpose of communicating thereto an accidental or false twist. This arrangement is specially suitable for giving to the roving two or more successive drawings, the apparatus being so arranged that the first drawing is effected in a drawing mechanism of any type and the second one in a mechanism in which the feeding devices, in addition to the feeding movement, have a rotary movement around the roving in order to communicate to it a twist and at the same time, convey the roving to the drawing rollers. In this manner the roving after it has undergone the first drawing receives a twist which reunites all its fibres and diminishes its diameter thereby causing it to remain in good condition for the purpose of undergoing the second drawing.

This already known mechanism yields good results but has two disadvantages in practice. In the first place the construction of the drawing apparatus is rendered very complicated owing to the necessity of giving to the feeding devices the double movement which produces the advance of the roving and the torsion of the same, and in consequence thereof the working of the mechanism is always rendered delicate. In the second place as the feeding devices which permit large drawings accompany the roving up to a point which is distant from the line of contact of the drawing rollers by less than the mean length of the fibres and on the other hand the false twist extends up to the point at which the feeding devices quit the roving, the result is that the second drawing is effected in an extension of the roving one part of which is untwisted and the other part twisted and this in certain cases is a disadvantage in order to obtain a perfect drawing.

These disadvantages are obviated by the drawing mechanism which forms the subject matter of the present invention, in which there is also given to the roving an accidental or false twist between the two drawings, but which is distinguished from the mechanism already known by the fact that the feeding devices of the second drawing set do not effect any more movement than the feeding movement which produces the feed or advance of the roving and the false twist is produced by a separate false torsion device of any suitable type.

In this mechanism the accidental or false torsion only extends up to the point of the false torsion device and when the roving is caught by the feeding devices of the second drawing set it is already untwisted.

An essential feature of this mechanism consists in the combination of a false torsion device between two drawing sets or mechanisms. In this way as the roving quits the drawing rollers of the first drawing set, it is subjected to a twist which diminishes its diameter and reunites all its fibres in such a way that when the roving is drawn in the second drawing set its width or diameter has already been considerably reduced and a relatively large drawing can be obtained without the risk of the fibres of the roving losing their cohesion and becoming separated, which would cause irregularities in the yarn.

As the roving is completely untwisted when it enters the second drawing set, it is convenient that the latter be such as to permit of large drawings, that is to say, that it is provided with feeding devices which accompany the roving up to a point which is distant from the drawing rollers by a distance which is less than the mean length of the fibres. In this way any irregular slip of the fibres in the roving which is being drawn and separation of the said fibres therein during the second drawing is avoided and consequently the considerable irregularities which the said slip and separation produce in the yarn are avoided also. These feeding devices may be constituted by belts, cylinders of small diameter, combinations of a belt with cylinders or with plates, etc.

The accompanying drawing shows diagrammatically in transverse section two constructional examples of the drawing mechanism of the present invention. In the

example shown in Figure 1 the second drawing set has as feeding devices endless belts. In the case of Figure 2 the second drawing set has as feeding devices cylinders of small diameter arranged close up to the drawing rollers.

The apparatus shown in Figure 1 has two drawing sets the first of which is constituted by the feed rollers —40—, —41—.

- 10 The intermediate rollers —6—, —7— and the drawing rollers —4—, —5—. The second drawing set is constituted by the feeding belts —31—, and the drawing cylinders —8—, —9—. The cylinder —41— is of 15 large diameter in order that its weight alone may exert a sufficient pressure on the roving —33— and the drawing roller —5— is loaded in the usual way by means of a curved rod —3— from which hangs a weight (not 20 shown in the drawing). In the second drawing set both the rollers —25— and —9— are loaded by means of the weighted rod —3'— and the pressure device —2'— which communicates to the two rollers the 25 pressure exerted by the weight.

The feeding belts —31—, —32— arranged in the usual way are driven by the rollers —25—, —26— and convey the fibres of the roving to a point situated relatively very 30 close to the drawing rollers, —8— and —9—.

- Between the drawing rollers —4—, —5— of the first drawing set and the feeding belts —31—, —32— of the second drawing set is 35 arranged the false torsion device —60— which communicates to the roving an accidental or false twist at the section between the rollers —4—, —5— and the point —63— of the device —60—. On emerging from 40 the drawing rollers —4—, —5— and due to the drawing which they have just undergone, the fibres of the roving are in an un-twisted state and desintegrated or separated from each other, but the accidental twist 45 given by the device —60— reunites all the fibres forming a roving of smaller width or diameter, thus avoiding that between the drawing rollers —4—, —5— and the feeding belts —31—, —32— the fibres may drop out 50 of the roving and cause irregularities in the yarn.

This reduction of the diameter of the roving augments the cohesion of the fibres with each other and prepares the roving to undergo the second drawing in the next drawing set, thus avoiding any separation of the fibres in this second drawing.

- 55 The false torsion device —60— may be of any suitable type which can be driven or operated in the usual way. In Figures 1 and 2 is shown as an example a false torsion device which is specially suitable for application to this mechanism. It is constituted by a member —60— approximately 60 of funnel shape provided with a split or

opening —62— for the introduction of the roving and having a point —63— with a helical groove for imparting the torsion to the roving. This member —60— rests simply by its own weight in the interior of 70 a ring —66— and is driven by this latter in its rotary movement. The ring —66— is mounted to rotate in a support —67— and receives rotary movement by a cord passing over the grooved pulley —61—. In 75 this way the member —60— can be withdrawn by simply grasping it with the hand and raising it and in the same way it can be put back in place after the introduction into it of the roving which is passed 80 through the opening —62—.

The peripheral speed of the feeding devices —31—, —32— only requires to be greater than that of the drawing rollers —4—, —5— to the extent necessary for the 85 roving to be permanently stretched between both devices. Notwithstanding in the majority of cases a better result is obtained if the speed of the feeding devices is substantially greater than that of the drawing 90 rollers —4—, —5— in such a way that there is produced between these rollers and the feeding devices —31—, —32— a certain drawing of the roving while it is being subjected to the false twist. This drawing with 95 the simultaneous twist contributes to the better arrangement in parallel of the fibres and to the regularization of the yarn because the twist accumulates at the parts of smaller diameter of the roving and increases the 100 resistance of these parts to the drawing by which the drawing is effected preferably at the more bulky parts of the roving which decrease in size until they become equalized 105 with the other.

The feeding devices of the second drawing set may be of any suitable type provided that they be of a type of feed devices which permit of large drawings because as the roving issues from the drawing rollers without any torsion it is necessary that the feeding devices accompany the said roving up to a point which is distant from the drawing rollers by an amount which is less than the mean length of the fibres.

110 In Figure 2 is shown an example of construction in which these feeding devices are constituted simply by two rollers —54—, —55— of small diameter arranged very close to the drawing rollers —8—, —9—. The lower roller —55— receives movement in any usual way and the upper roller —54— rests on the lower one by its own weight and as this is small, the pressure which this roller exerts on the fibres is also small and consequently allows the fibres driven by the drawing rollers to slip between the rollers —54— and —55—.

115 In order to avoid the unequal wear of the rollers and belts it is convenient to com- 120

5 municate to the roving a transverse to and fro movement in the well known way by means of the bar —57— and in this case the false torsion device is provided with the same to and fro movement as the bar —57—. This may be secured by mounting the supports of the false torsion devices on a bar which slides in convenient guides and by coupling this bar with the bar —57—.

10 The belts 31 and 32 in Figure 2 are of course in practice provided with guides to maintain these belts in the shape shown. These guides form no part of the present invention and they have been omitted to 15 avoid complicating the illustration and in the interest of clearness. Such guides may be seen in Figure 3 of applicant's prior Patent No. 1,213,744, granted January 23, 1917.

20 The positive drive for the cylinders 26 and 55 has also been omitted for clearness and because of the fact that this forms no part of the present invention. Such a drive means is shown in the U. S. Patent to 25 Cesoni, et al, No. 1,459,572, granted June 19, 1923.

In Figure 1 the cylinder 26 is shown as being positively driven by the friction wheels 100 and 101, the wheel 101 being 30 driven from an appropriate source of power.

In Figure 2 the cylinder 55 is shown as being driven by similar friction wheels 102 and 103.

I claim:

25 1. A large draft apparatus for drawing textile rovings composed of an initial drawing mechanism for giving the roving a primary or initial draft, twisting means for receiving the roving proceeding from the 40 initial drawing mechanism and communicating a false twist to this roving, and a final drawing mechanism for effecting a final draft of the roving after this latter has passed through the twisting head, said final 45 drawing mechanism being provided with feeding means positively driven, which compel the roving to advance and accompany it up quite close to the drawing rollers of said final drawing mechanism.

50 2. A large draft apparatus for drawing textile rovings which comprises an initial drawing mechanism composed of several pairs of rollers, a twisting head for receiving the roving coming from the initial drawing 55 mechanism and communicating to it a

false twist, and a final drawing mechanism formed by feeding means which receive the roving coming from the false twist device and a pair of drawing rollers which give the final draft to the roving held by 60 said feeding means, said feeding means communicating to the roving an advancing movement towards the drawing rollers and accompanying it up to a point quite near the said drawing rollers. 65

3. A large draft apparatus for drawing textile rovings which comprises an initial drawing mechanism formed by several pairs of rollers, a twisting head which receives the roving coming from the initial drawing 70 mechanism, and a final drawing mechanism which receives the roving coming from the twisting head and gives it the final draft, said final drawing mechanism being composed of a pair of endless feeding bands, 75 positively driven, which receive the roving from the twisting head and cause it to advance towards the drawing rollers accompanying it up quite close to these drawing rollers and a pair of drawing rollers which receive the roving delivered by 80 the feeding bands and give it the final draft.

4. A large draft apparatus for drawing textile rovings which comprises an initial 85 drawing mechanism formed by several pairs of rollers which revolve with increasing peripheral speeds, a twisting head which receives the roving coming from the initial drawing mechanism and communicates to 90 it a false twist, and a final drawing mechanism which receives the roving coming from the twisting head and gives it the final draft, said final drawing mechanism being composed of a pair of endless feeding bands, 95 positively driven, with a peripheral speed higher than the speed of the last pair of rollers of the initial drawing mechanism and a pair of drawing rollers which seize the roving conducted by the said feeding 100 bands and give it a draft, said feeding bands moving in such a way that they hold the roving between them and compel it to advance towards the drawing rollers and accompany it up to a point quite close to the 105 said drawing rollers.

In testimony whereof I have signed my name to this specification.

FERNANDO CASABLANCAS.
